US00D681444S

(12) **United States Design Patent**
Oja et al.

(10) **Patent No.:** US D681,444 S
(45) **Date of Patent:** ** May 7, 2013

(54) **PACKAGING**

(75) Inventors: **Mari-Annika Oja**, Helsinki (FI); **Mika Mattila**, Tampere (FI); **Oliverio Cruz-Diaz**, Tampere (FI)

(73) Assignee: **Nokia Corporation** (FI)

(**) Term: **14 Years**

(21) Appl. No.: **29/422,073**

(22) Filed: **May 16, 2012**

(51) LOC (9) Cl. **09-03**

(52) U.S. Cl.

USPC **D9/418**

(58) **Field of Classification Search** D9/415, D9/418, 501, 72, 739, 742, 753

See application file for complete search history.

(57) **CLAIM**

The ornamental design for packaging, as shown and described.

DESCRIPTION

FIG. 1 is a perspective view of packaging showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of packaging showing our new design;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a perspective view of packaging showing our new design;

FIG. 16 is a front view thereof;

FIG. 17 is a rear view thereof;
FIG. 18 is a left side view thereof;
FIG. 19 is a right side view thereof;
FIG. 20 is a top view thereof;
FIG. 21 is a bottom view thereof;
FIG. 22 is a perspective view of packaging showing our new design;
FIG. 23 is a front view thereof;
FIG. 24 is a rear view thereof;
FIG. 25 is a left side view thereof;
FIG. 26 is a right side view thereof;
FIG. 27 is a top view thereof;
FIG. 28 is a bottom view thereof;
FIG. 29 is a perspective view of packaging showing our new design;
FIG. 30 is a front view thereof;
FIG. 31 is a rear view thereof;
FIG. 32 is a left side view thereof;
FIG. 33 is a right side view thereof;
FIG. 34 is a top view thereof;
FIG. 35 is a bottom view thereof;
FIG. 36 is a perspective view of packaging showing our new design;
FIG. 37 is a front view thereof;
FIG. 38 is a rear view thereof;
FIG. 39 is a left side view thereof;
FIG. 40 is a right side view thereof;
FIG. 41 is a top view thereof;
FIG. 42 is a bottom view thereof;
FIG. 43 is a perspective view of packaging showing our new design;
FIG. 44 is a front view thereof;

FIG. 45 is a rear view thereof;
FIG. 46 is a left side view thereof;
FIG. 47 is a right side view thereof;
FIG. 48 is a top view thereof;
FIG. 49 is a bottom view thereof;
FIG. 50 is a perspective view of packaging showing our new design;
FIG. 51 is a front view thereof;
FIG. 52 is a rear view thereof;
FIG. 53 is a left side view thereof;
FIG. 54 is a right side view thereof;
FIG. 55 is a top view thereof;
FIG. 56 is a bottom view thereof;
FIG. 57 is a perspective view of packaging showing our new design;
FIG. 58 is a front view thereof;
FIG. 59 is a rear view thereof;
FIG. 60 is a left side view thereof;
FIG. 61 is a right side view thereof;
FIG. 62 is a top view thereof;
FIG. 63 is a bottom view thereof;
FIG. 64 is a perspective view of packaging showing our new design;
FIG. 65 is a front view thereof;
FIG. 66 is a rear view thereof;
FIG. 67 is a left side view thereof;
FIG. 68 is a right side view thereof;
FIG. 69 is a top view thereof; and,
FIG. 70 is a bottom view thereof.

The broken lines of the packaging in the figures and the unshaded regions therein are for illustrative purposes only and form no part of the claimed design.
